FIG. 1

FIG. 3

FIG. 2

FIG. 4

FIG. 5

FIG. 8

FIG. 6

FIG. 7

FIG. 1 is a perspective view of a combination whetter and sheath showing my new design with the closure tabs outfolded;

FIG. 2 is a front view of the combination whetter and sheath with only one of the closure tabs being illustrated outfolded.

FIG. 3 is a front view of the combination whetter and sheath with both tabs in closed position;

FIG. 4 is a left side view of the combination whetter and sheath;

FIG. 5 is a right side view of the combination whetter and sheath;

FIG. 6 is a top view of the combination whetter and sheath;

FIG. 7 is a bottom view of the combination whetter and sheath; and

FIG. 8 is a rear view of the combination whetter and sheath.

The fragmentary showing of the strap in FIGS. 2, 3, 4, 5, 6 and 8 is for convenience of illustration.

I claim:

The ornamental design for a combination whetter and sheath, substantially as shown and described.
